(57) **CLAIM**

The ornamental design for a lens assembly for headlamp, as shown and described.

DESCRIPTION

FIG. 1 is a left side perspective view of the replacement tail lens assembly of the present design;

FIG. 2 is a left side perspective view of the replacement tail lens assembly of the present design showing the cover of the tail lens assembly removed;

FIG. 3 is a front view of the replacement tail lens assembly of the present design;

FIG. 4 is a left side view of the replacement tail lens assembly of the present design;

FIG. 5 is a top sectional view of the replacement tail lens assembly of the present design; and,

FIG. 6 is a left perspective view of the replacement tail lens assembly of the present design showing the lens assembly installed on a vehicle.

The broken lines showing of the lens assembly in FIG. 5 and of the automobile in FIG. 6 are for illustrative purposes only and form no part of the claimed design.

CERTIFICATE OF CORRECTION

PATENT NO. : Des. 458,397 S
DATED : June 4, 2002
INVENTOR(S) : Brian A. Horowitz

Page 1 of 1

It is certified that error appears in the above-identified patent and that said Letters Patent is hereby corrected as shown below:

Title page.

DESCRIPTION

Lines 1-2, delete "replacement tail lens assembly" and insert -- lens assembly for headlamp --.
Lines 3-4, delete "replacement tail lens assembly" and insert -- lens assembly for headlamp --.
Line 5, delete "tail lens assembly" and insert -- lens assembly for headlamp --.
Line 6, delete "replacement tail lens assembly" and insert -- lens assembly for headlamp --.
Lines 8-9, delete "replacement tail lens assembly" and insert -- lens assembly for headlamp --.
Lines 10-11, delete "replacement tail lens assembly" and insert -- lens assembly for headlamp --.
Lines 12-13, delete "replacement tail lens assembly" and insert -- lens assembly for headlamp --.
Line 15, delete "FIG. 5" and insert -- FIGS. 1, 2, 4 and 5 and --.

Signed and Sealed this

Fifteenth Day of April, 2003
